(57) **CLAIM**

We claim the ornamental design for a bottle, as shown and described.

DESCRIPTION

FIG. 1 is a perspective view of a bottle, according to our new design, as viewed from the top, front, and one side thereof. FIG. 2 is a perspective view of the bottle, as viewed from the top, rear, and one side thereof.

FIG. 3 is a front elevation view of the bottle.

FIG. 4 is a rear elevation view of the bottle.

FIG. 5 is a top plan view of the bottle; and,

FIG. 6 is a side elevation view of the bottle, the opposite side being a mirror image thereof.

The broken lines on the neck of the bottle represent threads for engaging a cap for the bottle and form no part of the claimed design. The bottom surface of the bottle forms no part of the claimed design.
